UNITED STATES PATENT OFFICE

MEYER JACOBY AND ALBERT M. ZALKIND, OF NEW YORK, N. Y.; SAID ZALKIND
ASSIGNOR TO SAID JACOBY

ADJUSTABLE WIG

Application filed August 27, 1931. Serial No. 559,628.

This invention relates to wigs generally and more particularly to wigs adapted for use in connection with millinery display figures, or wherever a hat is worn with the said wig.

5 One of the objects of the invention is to produce a wig section for millinery display figures, comprising the lower portion of the wig, the upper edge of which is enclosed in a substantially wide protective band or binding to prevent the marring or destruction 10 of the said edge caused by the donning and removal of the hat from the display figure.

Another object of the invention is to provide a wig or wig section of this character with elastic or other adjustable means, so that one such section may be used for various head sizes within a given range.

Other objects and advantages will appear as the nature of the improvements is better understood, the invention consisting substantially in the novel arrangement and co-relation of parts herein fully described, and illustrated in the accompanying drawings, wherein similar reference characters are used 25 to describe corresponding parts throughout the several views, and then finally pointed out and specifically defined and indicated in the appended claims.

The disclosure made the basis of exemplifying the present inventive concept suggests a practical embodiment thereof, but the invention is not to be restricted to the exact details of this disclosure, and the latter, therefore, is to be understood from an illustrative, 35 rather than a restrictive standpoint.

In the drawings accompanying this specification

Figure 1 is a front view of a millinery display figure showing my invention as applied 40 thereto.

Fig. 2 is a perspective view of my improved wig and

Fig. 3 is a sectional view thereof taken on line 3—3 Fig. 2.

45 Referring now to the drawings in detail 5 indicates our improved wig which comprises a hirsute strip or wig section 6 having a foundation 7. The top edge of the wig is enclosed by a folded over band or strip 8, 50 made of fabric or other suitable material, and

is secured to the hair or wig section 6 by a row of stitches 9.

To suspend the wig from the head of a millinery display figure 10 or from a human head we provide a strip of tape 11 at the 55 front of the wig and a strip of tape 12 which is connected to the tape 11 at 13 and to the rear of the wig at 14.

In the form of our invention shown in Fig. 1 the strips 11 and 12 are preferably 60 made of elastic tape or webbing so that the wig may be adjustable and fit different sized heads.

In Fig. 2 we have shown the tape 11 secured at one end to the folded over band 8 65 by stitches 16, and at the opposite end of the tape 11 we have shown same as provided with one member 17 of a snap fastener adapted to be received in any one of a series of complementary members 18 of the said snap 70 fastener. The said strip or tape 11 is also provided at the center thereof with a part of a snap fastener and the tape 11 with the complementary members 18.

It will be understood that the upper tape 12 75 prevents the wig from dropping downwardly and the front tape 11 holds the wig snugly around the head.

With the above arrangement the wig is 80 adapted to be used for various sizes of display heads and thus avoid the necessity of having a different wig for each size of head as was formerly the common practice.

It will also be seen that due to the edge band or binding 8 the life and appearance 85 of the wig is greatly enhanced as no amount of putting on or taking off of the hat 20 will mar or destroy the edge of the wig.

From the foregoing, it will readily be seen 90 that we have provided a neat wig to be used for millinery display and other purposes, and one that may be readily adjusted to fit various sized heads and provided with means thereon to maintain at all times the said neat appearance of the wig.

We desire it understood that we do not 95 limit ourselves to the specific adjusting means described as other adjusting means may be used without departing from the 100 scope of the appended claims.

Having described our invention what we claim as new and desire to secure by Letters Patent is:

1. A wig comprising a hirsute strip, a protective band enclosing the upper edge of the said strip, an elastic tape connecting the ends of the said strip.
2. A wig comprising a hirsute strip, a protective band enclosing the upper edge of the said strip, an elastic tape connecting the ends of the said strip, and a second elastic secured to the rear of the wig and to the first mentioned tape.
3. A wig comprising a hirsute strip, a protective band enclosing the upper edge of the said strip, and means for adjusting the said strip to fit various sizes of heads.
4. A wig comprising a hirsute strip, a protective band enclosing the upper edge of the said strip, a tape for adjustably connecting the free ends of the said strip, a second tape secured at one end thereof to the wig, and means at the other end of the said second tape for adjustably securing same to the first mentioned tape.
5. A wig comprising a hair section adapted to fit around the head of the wearer, an elastic member connecting the ends thereof, and a tape secured to the hair section and to the elastic member to prevent the wig from slipping downwardly.
6. A wig comprising a hirsute strip adapted to fit around the head of the wearer, an elastic member connecting the ends thereof, and a second elastic member secured to the hirsute strip to prevent the wig from slipping downwardly.

In testimony whereof we hereunto affix our signatures.

MEYER JACOBY.
ALBERT M. ZALKIND.
